CHARLES H. HODGKINS, OF PITTSBURGH, PENNSYLVANIA, ASSIGNOR TO WESTINGHOUSE ELECTRIC & MANUFACTURING COMPANY, A CORPORATION OF PENNSYLVANIA.

STARTING MECHANISM FOR AUTOMOBILES.

Application filed June 25, 1920. Serial No. 391,632.

To all whom it may concern:

Be it known that I, CHARLES H. HODGKINS, a subject of the King of Great Britain, and a resident of Pittsburgh, in the county of Allegheny and State of Pennsylvania, have invented a new and useful Improvement in Starting Mechanism for Automobiles, of which the following is a specification.

10 My invention relates to starting mechanisms for automobiles and, particularly, to starting mechanisms for connecting electric motors to internal-combustion engines.

One object of my invention is to provide 15 a starting mechanism of the above indicated character that shall be provided with means for locking an auxiliary pinion, which meshes with the motor pinion, against rotation in order to swing it radially into mesh 20 with the engine gear wheel upon starting of the motor and that shall render such locking means inoperative upon meshing of the auxiliary pinion with the engine gear wheel.

25 It is customary, according to modern practice, to start the internal-combustion engine of an automobile by means of an electric motor and to provide means for connecting the motor to the engine before starting it and for automatically disconnecting 30 the motor from the engine after it is in operation. In many types of such starting mechanisms, the motor pinion is moved longitudinally along the armature shaft into

35 mesh with the engine gear wheel. However, such method of connecting the starting motor to the internal-combustion engine necessitates the rotating of the motor pinion within certain speed limits to effect meshing of the 40 pinion teeth with the teeth of the engine gear wheel. Moreover, the motor, which is operating at a considerable speed before meshing of the pinion with the gear wheel, is subjected to considerable shock by being 45 suddenly stopped upon meshing of the pinion with the gear wheel.

In a starting mechanism constructed in accordance with my invention, an auxiliary pinion, which meshes with the pinion on the 50 motor shaft, is so swung into mesh with the engine gear wheel as not to necessitate operating the motor at any predetermined speed to prevent so-called clashing of the gear teeth.

55 In the preferred form of practising my

invention, an auxiliary pinion, which meshes with the pinion mounted on the shaft of the starting motor, is rotatably mounted upon a bracket. The bracket is rotatably mounted concentric with the armature shaft and adjacent to the engine gear wheel. A latch member is mounted upon the auxiliary pinion and engages a notch in the bracket when the auxiliary pinion is out of mesh with the engine gear wheel and the motor is stationary.

In such structure, the bracket and the auxiliary pinion are rotated with the armature shaft, upon starting of the motor, to swing the auxiliary pinion into mesh with the engine gear wheel. Just before meshing of the auxiliary pinion with the engine gear wheel, a pin, which is mounted upon the motor frame, engages the latch member to free it from the notch in the bracket. The rotation of the auxiliary pinion supplies sufficient centrifugal force to maintain the latch member out of engagement with the notch in the bracket. After the engine is started, the engine gear wheel exerts force to swing the auxiliary pinion away from such gear wheel. A spring member is preferably connected between the motor frame and the bracket for biasing the auxiliary pinion away from the engine gear wheel.

In the accompanying drawing, Fig. 1 is a sectional view of a starting mechanism constructed in accordance with my invention;

Fig. 2 is a detail view in perspective showing the connection of the latch member to bracket, and

Fig. 3 is an end elevational view of the starting mechanism shown in Fig. 1.

Referring to the drawing, an electric motor 1, comprising an armature 2 and a field-magnet winding 3, is provided for starting an internal-combustion engine (not shown) having a flywheel gear 4. The motor 1 is provided with a frame 5 and an end bracket 6 having a projecting arm 7 which serves as a bearing for the armature shaft 8. A motor pinion 9 is rigidly connected to the shaft 8 in any suitable manner and preferably by a key, as shown in Fig. 1 of the drawing.

A U-shaped bracket 10, having two arms 11 and 12, is provided for rotation concentric with the armature shaft 8. The arm 12 has a bearing upon the shaft 8, and the arm 11 preferably has a bearing upon the

end bracket 6 of the motor. A short shaft 13, which carries an auxiliary pinion 14, is rotatably supported by the two arms 11 and 12 of the bracket 10. The auxiliary 5 pinion 14 meshes with the motor pinion 9 and is adapted to be swung into mesh with the engine gear wheel 4.

A latch member 15 is mounted upon the auxiliary pinion 14 and is provided with a 10 nose portion 16 which engages a notch 17 in the end of the arm 11, when the motor is stationary and the auxiliary pinion is out of mesh with the engine gear wheel. The latch member 15 is provided with a projecting portion 18, having a cam surface which is adapted to be engaged by a pin 19 when the auxiliary pinion meshes with the engine gear wheel. The pin 19 is preferably mounted upon the end bracket 6 of the 15 motor 1. The latch member is preferably constructed with the center of gravity near the end of it in order that the latch member may be held away from the arm 11, by 20 centrifugal force, when the auxiliary pinion 25 is rotating.

A spring member 20 is connected between a pin 21, which is mounted upon the arm 7 of the end bracket 6, and a pin 22, which is mounted on the arm 30 12 near the end thereof. Preferably, the pin 21 is so disposed relative to the pin 22 as to always permit the spring 20 to exert a force biasing the auxiliary pinion 14 away from the engine gear wheel 4. 35 It is to be understood, however, that the pin 21 may be so disposed relative to the pin 22 as to permit the spring member 20 to bias the auxiliary pinion 14, either into or out of engagement with the engine gear 40 wheel 4. A washer 23 is provided on the armature shaft between the arm 7 of the end bracket and the arm 12 of the U-shaped bracket 10 in order to permit the ready mounting of the arm 11 upon the end 45 bracket 6.

When the starting mechanism is in the position shown in the drawing, the auxiliary pinion 14 is locked to the arm 11 and, accordingly, it is caused to revolve with the 50 armature shaft 8 when the motor is started. If the motor is started, it is clear the pinion 14 is swung into mesh with the engine gear wheel 4 and the pin 9 raises the latch member 15 to permit the rotation of the pinion 55 when it meshes with the engine gear wheel. Furthermore, during the rotation of the pinion 14, the centrifugal force, acting upon the latch member 15, prevents such latch member from again engaging the notch in 60 the arm 11. When the internal-combustion engine is started, the engine gear wheel 4 exerts a force to swing the pinion 14 and the bracket 10 away from such gear wheel, and the pinion 14 cannot again be swung 65 into engagement with the engine gear wheel

until the rotation of such pinion is stopped to permit the latch 15 to engage the notch in the end of the arm 11.

Modifications in the mechanism and in the arrangement and location of parts may 70 be made within the spirit and scope of my invention and such modifications are intended to be covered by the appended claims.

I claim as my invention:—

1. In a starting mechanism for an automobile, the combination with a motor, an engine gear wheel, and a pinion connected to, and operated by, said motor, of means carried by said pinion for rigidly locking said pinion to the motor shaft to move the 75 pinion into mesh with the engine gear wheel, and means for rendering said locking means inoperative upon meshing of the pinion with the engine gear wheel, said locking means being responsive to centrifugal force where- 80 by it remains inoperative during the rotation of said pinion.

2. In a starting mechanism for an automobile, the combination with a motor, an engine gear wheel, and a pinion connected 90 to, and operated by, said motor, of means comprising a latch member mounted on said pinion for preventing rotation of the pinion to swing it into mesh with the engine gear wheel, and means for rendering said means 95 inoperative upon meshing of the pinion with the engine gear wheel.

3. In a starting mechanism for an automobile, the combination with a motor, an engine gear wheel, and a pinion connected 100 to, and operated by, said motor, of means mounted on said pinion for locking it against rotation to swing the pinion into mesh with the engine gear wheel, and means for rendering said locking means inoperative upon meshing of the pinion with the engine gear wheel. 105

4. In a starting mechanism for an automobile, the combination with a motor, an engine gear wheel, and a pinion connected 110 to, and operated by, said motor, of means comprising a latch member on said pinion responsive to centrifugal force to be rendered inoperative upon the rotation of the pinion for rigidly locking said pinion 115 against rotation to move the pinion into mesh with the engine gear wheel, and means mounted on said motor for rendering said locking means inoperative upon meshing of the pinion with the engine gear wheel. 120

5. In a starting mechanism for an automobile, the combination with a motor, an engine gear wheel, and a pinion connected to, and operated by, said motor, of means comprising a latch member mounted on said 125 pinion for locking said pinion to the motor shaft to move the pinion into mesh with the engine gear wheel, means for rendering said locking means inoperative upon meshing of the pinion with the engine gear wheel, and 130

means for biasing said pinion away from the engine gear wheel.

6. In a starting mechanism for an internal-combustion engine, the combination with a motor, an engine gear wheel, and a pinion connected to, and operated by, said motor, of means comprising a latch member mounted on said pinion for locking it against rotation to swing the pinion into mesh with the engine gear wheel when the motor is started, said engine gear wheel, when in rotation, serving to throw the pinion out of mesh, and a spring member for biasing the position of the pinion.
- 15 7. In a starting mechanism for an internal-combustion engine, the combination comprising a motor, a bracket rotatably mounted concentric with the shaft of said motor, a pinion rotatably mounted on said bracket and geared to said motor, an engine gear wheel, a latch member mounted on said pinion and registering with a notch in said bracket to prevent rotation of the pinion when it is out of mesh with the engine gear wheel, and means, upon operation of the motor and swinging of the pinion into mesh with the engine gear wheel, for automatically disconnecting said latch member from the bracket.
- 25 8. In a starting mechanism for an internal-combustion engine, the combination with a motor, an engine gear wheel, a bracket rotatably mounted concentric with the shaft of said motor, and a pinion ro-

tatably mounted on said bracket and geared to said motor, said pinion being adapted to mesh with the engine gear wheel, of a latch member mounted on said pinion and engaging a notch in the bracket to prevent rotation of the pinion when it is out of mesh with the engine gear wheel, and a pin mounted on the motor for lifting the latch out of said notch when the motor is started and the pinion is swung into mesh with the engine gear wheel, said latch being held away from the bracket by centrifugal force when the pinion is rotating.

9. In a starting mechanism for an internal-combustion engine, the combination with a motor, an engine gear wheel, a pinion fixedly mounted on the shaft of said motor, and a bracket rotatably mounted concentric with the shaft of said motor, of an auxiliary pinion rotatably mounted on said bracket and meshing with said motor pinion, of a latch member mounted on said auxiliary pinion and engaging a notch in said bracket to prevent rotation of the auxiliary pinion when it is out of mesh with the engine gear wheel, and a pin mounted on said motor for lifting the latch member out of said notch when the auxiliary is swung into mesh with the engine gear wheel.

In testimony whereof, I have hereunto subscribed my name this 21st day of June 1920.

CHARLES H. HODGKINS.
